CLAIM

The ornamental design for a combined sponge, squeegee, and fluid dispensing container with cap, as shown and described.

DESCRIPTION

FIG. 1 is a perspective view of the combined sponge, squeegee, and fluid dispensing container with cap showing our new design;

FIG. 2 is a side view thereof;

FIG. 3 is a top view thereof;

FIG. 4 is a bottom view thereof;

FIG. 5 is a rear view thereof; and,

FIG. 6 is a front view thereof.

FIG. 1

FIG. 3

FIG. 5

FIG. 2

FIG. 6

FIG. 4
